UNITED STATES PATENT OFFICE.

RICHARD A. CLARKE, OF CHATTANOOGA, TENNESSEE, ASSIGNOR OF ONE-HALF TO
THOMAS H. CLAY, OF CHATTANOOGA, TENNESSEE.

JACK STRUCTURE.

Application filed May 24, 1923. Serial No. 641,231.

To all whom it may concern:

Be it known that I, RICHARD A. CLARKE, a citizen of the United States, residing at Chattanooga, in the county of Hamilton and 5 State of Tennessee, have invented certain new and useful Improvements in Jack Structures, of which the following is a specification.

This invention relates to improvements 10 in lifting jacks.

The primary object of this invention is the provision of improvements in lifting jacks such as set forth in Patent #1,433,069, of the U. S., granted to me October 24, 1922.

15 An important object of this invention is the provision of a lifting jack embodying novel lifting means whereby the jack can be quickly and conveniently elevated or lowered.

20 A further object of this invention is the provision of improvements in steps or supporting devices for jacks.

Other objects or advantages of this invention will be apparent during the following 25 detailed description.

In the accompanying drawings, forming a part of this specification and wherein similar reference characters designate corresponding parts throughout the several views:

30 Figure 1 is a side elevation of the improved lifting jack.

Figure 2 is a fragmentary front elevation of the lower part of the lifting jack.

35 Figures 3 and 4 are transverse cross sectional views taken through the improved lifting jack showing respectively locked and unlocked positions of the lifting portion of the jack.

40 Figure 5 is an enlarged perspective view of an adjustable step member used in connection with the lifting jack.

Figure 6 is a side elevation of a novel type of handle used in connection with the lifting jack.

45 Figures 7 and 8 are transverse cross sectional views taken on their respective lines of Figure 6 of the drawings.

Figure 9 is a cross sectional view, taken substantially on the line 9—9 of Figure 1.

50 Figure 10 is a cross sectional view, analogous to Figure 9 although showing differently adjusted positions of the details thereof.

Figure 11 is a fragmentary cross sectional 55 view, taken through a portion of the lifting

jack, showing the manner in which a fulcrum bar thereof may operate in a supporting base.

In the drawings, wherein for the purpose of illustration is shown but the preferred embodiment of this invention, the letter A may generally designate the vehicle jack, which may include a supporting base B; standard C; lifting member or sleeve D; means E including a handle F for lifting 60 of the sleeve D upon the standard C, and a novel step member H for cooperation with the sleeve D.

It is preferred to provide the parts of the improved jack of stable construction and 70 durable material. To this end, the base B preferably comprises a supporting plate 15 having a longitudinal web 16 arranged in a vertical plane thereon. Preferably integral with the forward end of the vertical 75 web 16 is formed the vertical standard C, which is of novel construction. The body portion 17 of the standard C is preferably integrally formed with the base B, and provides a flat side surface 18 which is ar- 80

ranged in a plane at an acute angle with respect to the plane of the supporting web 16. A front surface 19 is preferably provided upon the standard body 17, arranged at a plane at right angles with respect to 85 the side 18; the juncture 20 provided longitudinally of the body 17 at the intersection of the sides 18 and 19 preferably being rounded to provide a convex surface. It is preferred to provide a lateral offset 21, 90 integral with the body 17, extending longitudinally of the standard C and oppositely arranged from the side 18, which converges to a point 22; the distance between the convex edge 20 of the body 17 and the edge 22 of the portion 21 designating the maximum width of the body 17. The front surface 23 of the offset 21 is arranged at a plane at an obtuse angle with respect to 95 the front surface 19, to provide a vertical edge 24, forwardly of the body 17, against which the sleeve D will abut, as will be subsequently described. At the side 25 of the body 17, directly opposite the side 18, it is preferred to attach a rack plat 26, as by 100 bolts 27, which upon a rear portion thereof is preferably provided with teeth 27 inclined upwardly as to provide the substantially horizontal supporting surfaces 29. The teeth 27 face laterally of the standard C in the 110

same direction as the offset 21 of the body portion 17 of said standard, although arranged vertically at the rear of said standard, whereas the offset 21 is forwardly and vertically arranged upon said standard.

Referring to the sleeve D, the same is preferably polygonal in cross section, including side walls 30 and 31, and front and rear walls 32 and 32^a respectively. The sleeve D is adapted for vertical reciprocation upon the standard C and preferably has the upper end thereof opened for detachable reception of a supporting seat or saddle 35. Adjacent the lower end of the side wall 31, it is preferred to provide a toothed plate 36, rigidly affixed to the side wall 31 as by means of bolts 37. The lower portion of the sleeve D may be cut away so that the teeth 38 of the plate 36 may extend into the passageway of the sleeve D, substantially as is illustrated in Figure 2 of the drawings, whereby they may cooperate upon the teeth 27 of the standard C. It is to be noted that the plate 36 is rigidly bolted to the sleeve D, and that the teeth thereof can only be intermeshed or disengaged with respect to the teeth 27 of the standard C by lateral shifting of the entire sleeve D. Normally, when the teeth of the standard and sleeve intermesh the sleeve bears a relation to the standard C, substantially as is illustrated in Figure 3 of the drawings. In this position, the front wall 32 of the sleeve may abut the vertical edge 24 forwardly of the standard body 17, while the side wall 30 of the sleeve D may abut the concaved vertical edge 20 of the standard body 17. The vertical edge 24 of the body 17 acts substantially as a fulcrum for the lateral movement of the sleeve D, so that the same may be shifted into the position illustrated in Figure 4 of the drawings, for disengagement of the standard and sleeve teeth. In this position, the inside surface of the sleeve wall 30 rests in abutting engagement with the side surface 18 of the standard body 17. As the length and width of the standard C are substantially equal to the clearance provided in the passageway 40 of the sleeve D, it is obvious that the sleeve may have a lateral rocking movement, such as above described, without liability of loose play laterally or forwardly of the standard C.

Referring to the lifting means E, the same preferably comprises a fulcrum lever 45, bifurcated at its lower end as to provide spaced depending arms 47 and 48 adapted to straddle the base web 16, and to be pivotally secured thereto at their lower ends as by means of a pin 49. The aperture 50 in the web 16 which receives the pin 49 permits the pin to rock laterally with respect to the plane of the web 16,

so that the fulcrum lever 45 may be tipped laterally with respect to the plane of the supporting web 16 to a limited degree, substantially as is illustrated by the full and dotted lines in Figure 11 of the drawings. A shoulder 51 is preferably provided upon the web 16 rearwardly of the fulcrum lever 45, against which the latter may contact to limit the rear movement of the same. The lever 45 is, of course, movable in a vertical plane toward the standard C. The upper end of the supporting fulcrum lever 45 is preferably bifurcated, as at 52, whereby the same may be pivotally attached to the depending lug 53 of an operating lever 80 or handle 54, as by means of a pin 55^a.

The lifting lever 54, in the nature of an integral structure, includes the body portion 55 having the longitudinal reinforcing web 56 extending from a side thereof. The lug 53 depends intermediate the ends of the body portion 55. At its forward end the body portion 55 is preferably provided with a forked structure providing spaced lifting arms 58 having recesses 59 inwardly thereof adjacent their outer ends. A plurality of prongs 60 are provided at the opposite end of the body portion 55, each of which are substantially T-shaped in cross section providing a substantially vertical plate portion 62, and a flange 63 extending centrally and longitudinally therewith and arranged in a plane at right angles thereto. The fingers are arranged for the purpose indicated in my patent above referred to, for disposition within the opening 63 of the socket end 64 of the handle F.

Referring to the step H, the same is preferably formed to provide a forward supporting portion 65 having the upper surface 105 thereof substantially arranged at right angles to the rear surface 66 thereof. Attaching arms 67 and 68 are preferably provided, extending in parallel relation, at right angles to the surface 66, and of course integral 110 with the forward portion 65, which are adapted to receive the lifting sleeve D therebetween. At their free ends, the attaching arms 67 and 68 preferably provided substantially vertical shoulders 70 which are adapted for engagement against upwardly extending projections 71 of lugs 72 arranged on opposite sides of the lifting sleeve D and preferably integral therewith. The step H is assembled upon the sleeve D, so that the forward portion 65 extends outwardly from the front surface of said sleeve, and has the attaching arms lying in substantially abutting relation upon opposite side surfaces of the attaching sleeve D with the shoulders 70 engaging in firm connection the extensions 71 of the lugs 72. In this position the rear surface 66 rests in abutting relation against the forward surface of the sleeve D. Any weight coming on the step H will 120

of course be supported thereby although the step H may be quickly and conveniently detached from the sleeve D so that the same may be selectively positioned upon any of the series of lugs 72 which are vertically arranged at opposite sides of said sleeve.

Referring to the handle F, the same is preferably longitudinally adjustable and includes the socket portion 64 above mentioned, and the extension handle 75. The socket portion 64 at its forward end is provided with a substantially T-shaped slot 63 for the reception of the T-shaped prongs 60. A portion 76 of the socket section 64 is preferably provided with a guide groove 77 inwardly of a side face thereof, within which the extension section 75 may fit for longitudinal adjustment. A clamping bolt 79, preferably of the wing nut type, is provided upon the extension section 75, transversely extending through a longitudinal slot 80 provided in the portion 76 of the socket section 64, whereby the sections 64 and 75 may be clamped together in any predetermined longitudinal adjustment. A handle grip 81 is preferably provided upon the free end of the extension section 75.

Referring to the operation of the improved jack, the step H having been attached upon a pair of the prongs 72 as above described, it is merely necessary to place the jack below the article to be worked upon. The handle F having been attached upon one of the prongs 60, it is merely necessary to laterally shift the lifting means E for a slight degree, as above outlined, until the intermeshing teeth of the standard and lifting sleeves are out of engagement. By bearing upon the handle F, the sleeve D may then be elevated for jacking purposes. By return shifting of the lifting means E, the teeth of the lifting sleeve and the standard may again be in relative mesh at the new elevation for supporting an article. This jacking operation may be continued until the operation is complete. The saddle or seat 35 may of course be used for engaging an article to be elevated in lieu of the detachable step H.

From the foregoing description of this invention, it is very apparent that a lifting jack has been provided, which is relatively simple in construction, and the parts of which are so assembled that the same can be quickly and conveniently used for jacking purposes. The outstanding features of the invention are the detachable and adjustable step H, which may be selectively used in place of the saddle 35; the novel means by which the lift may be elevated upon the jack standard, and by means of which the jack may be conveniently and safely lowered when a weight is imposed upon the step thereof. It is extremely difficult in the type of jack such as provides an ordinary pawl

and rack to lower the same when a load is imposed thereon. However it is obvious that with the lifting means here employed, lowering may be effected as conveniently as elevation.

A further important feature of the invention is the adjustable handle.

Various changes in the shape, size and arrangement of parts may be made to the form of invention herein shown and described, without departing from the spirit of the invention or the scope of the claims.

I claim:

1. A jack comprising a base, a standard, a lifting member movably arranged upon the standard, means on the standard and lifting member for engagement whereby they may be held at a predetermined adjustment, and common means for laterally shifting of the lifting member to permit disconnection of the parts of the first mentioned means and then shifting the lifting member vertically along the standard.

2. A jack comprising a standard having a series of teeth arranged therealong, and a lifting member slideable upon the standard and having limited turning movement thereon, said lifting member having teeth thereon adapted for engagement with the teeth of said standard when the lifting member is turned in one direction and operating means for said lifting member mounted for vertical swinging movement and horizontal rocking movement whereby said lifting member may be turned upon said standard so that the teeth thereof may be disengaged from the teeth of the standard and the lifting member then moved along the standard.

3. As an article of manufacture, a jack structure comprising a standard, a lifting member movable along the standard, a series of lugs oppositely extending from the sides of said lifting member having extensions upwardly thereon, a detachable step associated with said lifting member including attaching arms for cooperation against the upwardly extending portions of said lugs so that said step may extend forwardly of said lifting member, and an operating lever having engagement with said lugs for imparting vertical movement to said lifting member.

4. A jack comprising a base, a standard supported by the base, a lifting member slideable upon said standard, a fulcrum lever pivoted to the base, and a lifting lever pivoted to the fulcrum lever for adjustment of the lifting member along said standard, said lifting member being laterally movable by operation of said lifting lever whereby the same may be connected or disconnected with respect to said standard.

5. A jack structure comprising a base, a standard having a series of teeth therealong, a lifting member having teeth thereon for

connection or disconnection with the teeth of said standard, a fulcrum lever pivoted upon said base, and a lifting lever pivoted upon said fulcrum lever for engagement with said lifting member whereby the latter may be moved so that the teeth thereof may engage or disengage the teeth of the standard.

6. A jack comprising a base, a standard

for the base, a lifting member movable along the standard, means for connection of the lifting member to the standard, and a lifting device fulcrumed upon said base for lateral movement whereby the lifting member may be laterally moved upon said standard for disconnection of the first mentioned means.

RICHARD A. CLARKE.
